Patented May 25, 1909.

UNITED STATES PATENT OFFICE.

SIDNEY A. REEVE, OF WORCESTER, MASSACHUSETTS, ASSIGNOR TO CHARLES F. BROWN,
TRUSTEE, OF READING, MASSACHUSETTS.

COMPOUND EXPLOSIVE-ENGINE.

No. 922,509.

Specification of Letters Patent.

Patented May 25, 1909.

Application filed June 18, 1906. Serial No. 322,204.

To all whom it may concern:

Be it known that I, SIDNEY A. REEVE, a citizen of the United States, residing at Worcester, in the county of Worcester and 5 State of Massachusetts, have invented certain new and useful Improvements in Compound Explosive-Engines, of which the following specification and accompanying drawings illustrate the invention in a form 10 which I now regard as the best out of the various forms in which it may be embodied.

This invention relates to internal combustion engines having outside compression and using two or more stages of pressure in order 15 that a high maximum pressure, high efficiency and high power per unit of engine-weight may be attained. In a prior application, Ser. No. 267,719, I have claimed the general type of apparatus in connection 20 with which my present improvements are preferably employed.

Among the objects of the present invention are the following matters: first, the provision of means for employing liquid fuel 25 and supplying it within the pressure circuit in such manner that its gas or vapor will be in a desired ratio to the quantity of compressed air which enters into the explosive charge. Secondly, the improved manner of 30 controlling, distributing and metering the air supply, to the end that a single air compressor may supply to the motor both pure air and carburized or fuel-laden air, and to the further end that a compressor with a 35 fixed intake may properly charge the explosion cylinder at all pressures without loss of fuel. Thirdly, the attainment in a system of this kind, using an explosion motor of the two-cycle type, of an extended expansion 40 within the explosion cylinder. Fourthly, an improved plan of governing the engine according to load. Some of these objects also apply broadly to solid as well as liquid fuel as will be hereinafter pointed out.

45 Of the accompanying drawings, Figure 1 represents a diagrammatic section and elevation of an internal-combustion motor system constructed according to my invention.

Fig. 2 represents a cross-section of the 50 2-position valve included in the starting arrangements.

The same reference characters represent the same parts in both views.

In the drawings, 10 is an explosion motor 55 of the two-cycle type having a cylinder 11,

and water-jacket 12, and a piston 13 arranged with the usual baffle 14 between the ports in the walls of the cylinder. Said piston is formed at one end of a moving piston structure 15 having at its opposite end the 60 piston 16 of the air compressor 17.

18 is the air-compressor cylinder and 19 its water-jacket.

The air compressor 17 supplies the first stage of compression of the charge, which 65 latter enters the explosion motor 10 at the termination of the working stroke and is compressed therein to a second and higher stage of compression and then exploded at the top of the stroke by an igniter 20. The 70 exhaust moves out through an exhaust-pipe 21 into a cooling chamber 22 containing a body of water 23 where steam is made, the steam and gases having an exit through a continuation 24 of the exhaust-pipe into a 75 low-pressure expander 25 of the steam-engine type. I have here shown the explosion motor 10 connected by a rocking beam 26 and pitman 27 with a crank-plate on a shaft 28, and have shown the pitman 29 of the 80 low-pressure cylinder connected with a crank-plate which is shown as geared to the same shaft 28. Thus both high-pressure and low-pressure motor cylinders drive the same shaft and have stroke for stroke. This 85 drawing however is, for illustrative purposes, made somewhat more complex in relation to crank-connections than would be necessary in practice. Other component parts also, where they come within the skill 90 of the designer, or where their specific organization is not of the essence of my present invention, are shown of a form to illustrate the invention in the clearest manner and do not necessarily represent the best 95 engineering practice of the present day.

Two exits are provided from the air compressor 17 by way of pipes 30 31 the outlets to which are controlled respectively by check-valves 101 102, the latter being 100 loaded more heavily than the former by a spring.

33 is the compressor admission-valve.

It will be seen that the port of valve 101 is located some distance from the head of 105 the cylinder while the port of valve 102 is located at the very end. Hence the valve 101 is overrun before the termination of the compressing stroke and thereafter the remaining air must pass out through valve 110

102. The general object of this arrangement is to supply at all pressures a fixed volume of air adapted for carburization.

In the pipe 31 leading from valve 102 is a carbureter 34 having a fuel-supply pipe 35 and an overflow pipe 36. Pipe 35 is connected with a fuel pump 37 driven from a counter-shaft 38. The overflow pipe 36 contains a trap 39 for releasing liquid but not gas. This trap includes a reservoir 40, a float 41 therein partly balanced in weight by a spring 32, and a check-valve 42 operated by the float for obstructing the overflow or by-pass pipe 36. The pump 37 supplies more fuel than the carbureter 34 evaporates, the excess collecting in trap 39 and flowing back to the suction side of the pump when float 41 lifts the valve 42. Thus a constant level of fuel is maintained within the carbureter, and the air passing through or over the volatile fuel, takes up a quantity of vapor in substantial proportion to the quantity of air. This method of carbureting, namely by entraining liquid fuel in substantial proportion to the quantity of air passing through the carbureter, from a constant-level pool containing an excess quantity of the fuel and maintained under the pressure of the air-conduit or some derived pressure, gives an automatic proportion between air and fuel in the combustible charge which cannot be attained without considerable complication by fuel-pump metering expedients. As various kinds of carbureters having the characteristics just mentioned would be suitable for this situation, I am not confined to the exact construction here given as an illustration of the principle.

40. In the compressor discharge-pipes 30 31 are placed intercoolers 43 44 for bringing the temperature of the compressed air back to or toward its initial point. If the intercoolers restore the temperature of this first stage to atmospheric, then (neglecting surplus heat of the explosion cylinder 11) the explosion cylinder may give a further compression in the same proportion to the first-stage pressure as the first-stage pressure was to atmosphere without resulting in a higher temperature than the temperature of the first compression. Thus if the first stage was six atmospheres the second stage, by reason of intercooling, may be thirty-six atmospheres 55 without attaining a final temperature beyond the preignition point. This of course results in enormously high explosion pressures, say 2000 to 3000 pounds per sq. in., but, taking place in a small cylinder they 60 may be handled without producing excessive strains or requiring massive parts. The pressures given are illustrative merely and may be departed from in practice without depriving the cycle of its essential character.

65. Air enters the explosion cylinder 11 through

an admission-port 45 at or near the outer end of the stroke and leaves through an opposite exhaust-port 46 the same as in the ordinary two-cycle engine. In addition, I provide a fuel-admission-port 47 and an auxiliary exhaust-port 48 located opposite each other some distance up the cylinder toward the head end and these ports I control respectively by means of a puppet fuel-valve 49 and a puppet exhaust-valve 50, actuated through tappets 51 by an eccentric 52 on the counter-shaft 38. When the piston 13 on its out-stroke uncovers the main entrance- and exhaust-ports 45 46, the exploded charge is exhausted through the port 46 and a charge of air enters through port 45 and assists in driving out the dead gases. Meanwhile the auxiliary exhaust-valve 50 has opened and later the fuel-valve 49 has opened so that although the piston starts on its return stroke and covers the ports 45 46 there is still a free exhaust through auxiliary port 48 and a free fuel entrance through fuel-port 47, the effect of which is to charge the explosion cylinder 11 with fresh charge to the extent of less than its full volume and permit an expansion of the exploded charge to a greater final volume at the point of exhaust than the initial volume of charge. This improves the efficiency. On the out-stroke the auxiliary exhaust-valve 48 keeps the cylinder closed for this super-expansion until the main exhaust-port 46 has become uncovered. I further provide an ante-chamber or vestibule 53 to the fuel-port 47 and an auxiliary puppet air-admission valve 54 from the air-pipe 30 into this ante-chamber. The valve 54 remains open slightly after fuel-valve 49 closes, and gives a final puff of air through the fuel-port which cleans out the remnant of fuel therein and sends it to be further compressed and exploded, instead of wasting that remnant when the fuel-port becomes uncovered on the working stroke of the piston. The order of opening of the three puppet valves is: first, the auxiliary exhaust-valve 50, then the auxiliary air-valve 54, and finally the fuel-valve 49, and the closing is in the inverse order, fuel-valve closing first, next air-valve, and finally exhaust-valve.

I have shown a shaft governor 55 on the counter-shaft 38 controlling the eccentric 52, its primary object being to vary the time of opening of the fuel-valve 49 according to the load on the engine. Thus, at maximum load the fuel-valve would have its longest opening, while at zero load it might have no opening at all. The governor, in addition, may have some useful effect on the exhaust-valve 50, causing it to close early at light loads and thus increase the compression pressure and maintain power and efficiency when the fuel charge is very light.

The introduction of the governor action on

fuel-valve 49 makes desirable the use of a loaded check-valve 56 connecting the compressor delivery-pipe 31 with compressor delivery-pipe 30, so that when the fuel-valve 5 valve chokes exit into the explosion cylinder through pipe 31 the back-pressure in said pipe may be released into the pipe 30. This check-valve may be loaded to, say 2 lbs. pressure. The governor 52 also acts on an eccentric 57 which operates the valve of the steam cylinder 25 and times it conformably with the fuel valve 49 and exhaust-valve 50, thus making the draft of heat and fluids from cooling-chamber 22 conform with the supply thereto and keeping the intermediate pressures stable under varying loads.

Water flows in a serial order through the jackets and pistons and the cooling chamber as follows. It is forced by a pump 58 first through pipe 59 into the water-jacket 19 of the air-compressor, and thence passes through a telescopic fitting 60 into the compressor-piston end of the moving piston structure 15. A vertical partition 61 divides the interior upper half of this piston structure into compressor-piston end and exploder-piston end, and a horizontal partition 62 separates the upper half from the lower half but permits water passage around the ends of the partition and from one end to the other of the piston-structure. The water which enters the compressor-piston 16 from the compressor-cylinder jacket bathes the inside of and cools said piston and then flows to the opposite end of the piston structure and cools the exploder-piston 13. It then passes out through a second telescopic fitting 63 and divides at 64, a part going through pipe 65 to the explosion cylinder jacket 12 and thence through pipe 66 to the cooling chamber 22, and another part going by a pipe 67 to a release valve 68 operated by a diaphragm controller 69 which is subject to the water-level in chamber 22. Any suitable water-level controller will perform this office, which is to maintain a substantially constant level of water in chamber 22 by releasing any excess through the valve 68.

In addition to the jacket and piston water-supplies of the explosion cylinder 12 I have shown three spray injections, one by way of a pipe 70 in the head of the explosion cylinder 11 for spraying water into the cylinder at the moment of maximum pressure, thus cooling the gases, conserving their heat in the form of steam, and assisting in the expansive power by reason of the large volume of steam; and a second injection at the moment of exhaust through a pipe 71 upon the back of the exhaust-valve 50 in order to cool said valve and also absorb some of the heat of the exhaust. The first of these water injections is supplied by a pump 72, connected with pipe 70 which contains an air-chamber 73 for storing elastic air-pressure above an accumu-

lation of water. A valve 74 at the water outlet of this chamber is controlled by a trip-cam 75 on the shaft 38 which opens the valve and injects a spray of water into the explosion cylinder at or about the time of maximum pressure. A valve 76 in the pipe 71 operated by a similar cam-trip 77 injects a spray against the exhaust-valve 50 at or just after the time of exhaust. An additional spray may be had from the water-jacket through an inwardly-opening check-valve 78 in the head of the cylinder which is opened by the water pressure at the time of exhaust, for the purpose of aiding in the scavenging by the formation of a large volume of steam, at the instant of exhaust, at the end of the cylinder farthest from the ports 47 and 48. All of these sprays serve to relieve the cooling chamber 22 of part of its duty and thus reduce its size and cost. The cooling chamber, however, preserves a dominant pool into which any excess of water from the sprays is merged and afterward evaporated by the exhaust gases, whereby I am enabled to greatly simplify the problem of regulating the quantity of sprayed water to the quantity and temperature of heat in the exploded gases.

Storage of exploded gases under pressure for starting purposes is effected by connecting a reservoir tank 79 by a pipe 80 with the interior of the explosion cylinder 11 at a point between the beginning and end of the stroke of piston 13, thereby abstracting a portion of the exploded gases after they have performed useful work upon piston 13. A check-valve 81 in said pipe prevents the return of the gases, and when tank 79 has been filled to a balancing pressure the gases no longer flow to the tank. Outlet from the tank 79 is by way of a pipe 82 leading to the casing of a 2-position valve 83 which has other pipes 84 and 85 leading respectively to the low-pressure cylinder 25, to the cooling chamber 22, and to the atmosphere. When in one position, illustrated in full lines in Fig. 2, this valve connects the explosion cylinder 11 with the low-pressure cylinder 25 by way of the cooling chamber and shuts off the pressure-tank 79. This is its normal running position. In the other position, shown in dotted lines in Fig. 2, the explosion cylinder is connected with the atmosphere and the low-pressure cylinder 25 is connected with tank 79. This is the starting position. In this latter position the motor is started by stored pressure from the tank 79 admitted to the low-pressure motor 25, while the high-pressure cylinder 11 exhausts to the atmosphere. Starting is thus effected without any interference with the functions of the explosion cylinder and the starting pressure may be left on through several revolutions or as long as it will last. The cooling chamber also gets a preliminary warming by the exhaust gases passing to atmosphere. As the

fly-wheel acquires speed the valve 83 may be turned to its running position. Compression-pressures will then pick up and the engine will go into normal operation under high pressure with compound compression and compound expansion.

The water system and starting devices above set forth, while desirable features, are not essential to my present invention.

10 Describing more fully the cycle of operations, it will be seen that the compressor 17 takes in at each leftward stroke a fixed volume of air and on the out-stroke sends it out toward the explosion cylinder 10, into which 15 the air enters and receives a further and final stage of compression. The entering charge blows out the products of combustion from the previous explosion and these, traversing the cooling chamber 22 where they are 20 quenched and create a body of steam, pass together with the steam into low-pressure engine 25 and do further useful work on the piston of the latter. In passing from the compressor to the explosion cylinder the air 25 is intercooled both in the pipe 30 and in the pipe 31 by means of the intercoolers 43 44 so that the further stage of compression in the explosion cylinder will not cause preignition. On the expansion side, the products of com- 30 bustion are cooled both by the body of water 23 and by the sprays from the nozzles 70, 71 and 78. The water-cooling is effective in transforming the heat to a lower-temperature, more usable form. Under special con- 35 ditions, however, I may omit cooling on the expansion side.

Compressor 18 is preferably of such capacity that at the maximum pressure permitted in the system it will furnish a slight excess of 40 air over that required for the explosive charge. At lower pressures a greater air excess is provided, as will be later explained. This air is used for scavenging and it escapes into the cylinder 11 as soon as admission- 45 port 45 is uncovered by the piston and before fuel-valve 49 is opened. It thus clears out the previous charge and a part of it may pass on through the exhaust 46 and perform work in the low-pressure engine 25. Such air as 50 thus passes on ahead of the charge is somewhat warmed by the cylinder and gives back most of the work expended in compressing it. By this means I provide a substantial improvement over ordinary single-expansion 55 scavenging engines which are not capable of using either the exhaust gases or the scavenging air which passes out of the exhaust for further useful expansion.

At the lower or sub-maximum pressures 60 the excess air will be larger in volume. Since the same quantity of compressed air at a lower pressure will have a larger volume than at a higher pressure and this volume in the present engine must be accommodated longitudinally, it is plain that the explosion

cylinder 11 will not hold the whole volume sent out by the compressor 17, the cubic contents of which are shown as considerably in excess of cylinder 11. It will now be apparent that if all of the air which compressor 17 70 delivers were charged with fuel some of it at low pressures would escape into the exhaust-pipe 21 unburned when the ports 45 46 are uncovered by the piston as shown in Fig. 1. Such waste of fuel would be very objection- 75 able and I avoid it by the arrangement of the compressor discharge-valves 101 102. On the compressing stroke of piston 16 air will begin to escape past valve 101 as soon as the pressure in the compressor has overcome the 80 back-pressure, and it will continue to escape through the same valve until this valve has been overrun by the piston. Up to that time the stronger loading of valve 102 prevents the air from choosing the path past 102, 85 but as soon as valve 101 is overrun then all of the discharge takes place past 102. It is this final volume of air which, passing through pipe 31, becomes or may become fuel-charged in the carbureter 34, the arrangement 90 being such that more fuel will be taken up than is necessary to form an explosive mixture and the final ingredient of air must be supplied to the explosion cylinder through the admission-port 45 (or through port 47). 95 The fuel, on entering, finds some air already in the cylinder; some air enters through 53 simultaneously with the vapor, and the whole forms an explosive mixture. It will be seen that the 101 102 valve arrangement 100 effects a metering of the fuel-charge to the explosion cylinder, which metering the cylinder 11 is unable to perform for itself, being of the two-cycle type where both admission and exhaust-passages are open at the same 105 time. It can take only what is blown into it. The volume of air which goes out through valve 102 is bound to enter cylinder 11 and remain there without overflow, because it has been squeezed up into a definite compass 110 which is so calculated as not to exceed the capacity of cylinder 11.

In the arrangement here given the metering device limits the fuel volume to a definite maximum irrespective of pressure and prevents overflow of unburned fuel from the explosion cylinder; but by reason of the introduction of relief-valve 56 and governing of the fuel-valve 49 the metering device does not insure the same volume of fuel in the explosion cylinder at all times or loads upon the engine. Thus if the governor shuts down the valve 49 entirely, at no load or negative load, no fuel reaches the explosion cylinder, and all of the air which went but past valve 102 is 125 shunted across through valve 56 into the pipe 30 and goes into and through the explosion cylinder as scavenging air or as unburned air. The action of the governor, therefore changes the proportions of the mix- 130

ture according to load and imposes a limitation upon the rise of pressures due to combustion. It is not essential to vary the mixture but such variation is useful in many instances.

It is obvious that the described means for by-passing compressed air around the point of fuel-supply into the low-pressure pipe 21 in varying quantities according to the back-pressure in said pipe is a useful energy-conserving and regulative expedient regardless of the particular method of compressor discharge, or of fuel supply, and regardless of whether or not the air is by-passed through the combustion-cylinder.

The plural-stage compression and expansion here provided enable me to effect a new distribution of heat between the jacket and exhaust of the explosion cylinder. In the ordinary Otto or in any single-stage-expansion internal-combustion engine it is an object to have as little heat as possible go out of the exhaust. Hence, owing to the high temperatures, much of the total heat goes into the water-jacket or through the cylinder walls. In the ordinary gas engines the proportion of waste heat going to the exhaust and jacket respectively is about equal, being about 40% of the total to each. I aim to bring about a new proportion; that is, by decreasing the cubic dimensions, and hence the heat-transmitting surface of the explosion cylinder per unit of fuel in the charge, I am able to send less heat to the jacket and more to the exhaust. If this new proportion of jacket-heat to exhaust-heat be made about 1:4, that ratio will substantially correspond to the quantities of heat required respectively to raise a given weight of cold water to the boiling point and to evaporate it at that temperature. Therefore, since the water-jacket 12 feeds the cooling chamber 22, I am able to evaporate in the cooling chamber, by means of the heat which goes out of the exhaust, nearly if not quite all of the water which has been required to keep the cylinder walls cool. This ratio, if approximately attained, need not be rigidly observed, since I may provide for a passage of water through the jacket 12 supplementary to that called for by the chamber 23. The proportion of jacket water and cooling-chamber water is somewhat varied by the action of the water sprays hereinbefore described. It is observable however that the hotter the exhaust gases and hence the higher the temperature within the explosion cylinder, the more water will be evaporated in cooling chamber 22 and the more water will flow through the jacket 12 to keep down the temperature of the cylinder walls, since under such conditions the controller 69 closes the by-pass valve 68 until normal level is restored in cooling chamber 22 through the pipe 66.

It will be seen that the carbureter 34 in its representative aspect is a device for carbureting air so as to provide an aeriform fuel. The carbureter might be replaced by a coal-gas (Siemens) producer operating under pressure.

What I claim as new and desire to secure by Letters Patent is:

1. A compound heat engine comprising an internal-combustion motor, a low-pressure motor operated by the pressure of the exhaust gases from said high-pressure motor, an air-compressor driven by the high-pressure motor for charging the latter, a compressed-air conduit leading from said compressor to the high-pressure motor and having a fuel-entraining device, and means for by-passing a portion of the compressed air unburned around said fuel-entraining device to the low-pressure motor against the back-pressure of the high-pressure exhaust. 80

2. A compound internal-combustion engine comprising a low-stage air-compressor, a high-stage-compressing explosion cylinder and piston for driving the compressor, a low-stage motor operated by the high-stage exhaust, a liquid-fuel carbureter interposed between the compressor and explosion cylinder, and means controlled automatically by the back-pressure of said exhaust for by-passing variable quantities of compressed air unburned to the low-stage motor. 95

3. A compound internal-combustion engine comprising an air-compressor, a high-pressure explosion-motor connected to drive the same, a low-pressure motor operated by the high-pressure exhaust, and a liquid-fuel carbureter located in the compressed-air line between compressor and high-pressure motor and having means for automatically maintaining a constant-level pool of fuel under 100 the compressed-air pressure subject to entrainment by the passing air-current. 105

4. A compound internal-combustion engine comprising a high-pressure internal-compressing explosion motor, a low-pressure motor operated by the high-pressure exhaust, an air-compressor driven by said high-pressure motor for imparting the first stage of charge-compression and having a combustion-air outlet to the high-pressure motor 110 and an excess-air outlet to the low-pressure motor, and means whereby said combustion-air outlet is opened at a predetermined point in the compression stroke. 115

5. A compound internal-combustion engine comprising a two-stroke-cycle explosion motor adapted to receive its combustible charge during or about the exhaust period of the preceding charge, a low-pressure motor operated by the high-pressure exhaust, an air-compressor driven by the high-pressure motor and adapted to furnish both combustion air and excess air, and means controlled 125

by the back-pressure of the high-pressure exhaust for varying the quantity of excess air inversely to said pressure.

6. A compound internal-combustion engine comprising a two-stroke-cycle internal-compressing explosion motor charged during or about its exhaust period, a low-pressure motor operated by the high-pressure exhaust, an air-compressor coupled to the high-pressure motor, a combustion-air conduit leading from the compressor to the high-pressure motor and containing a liquid-fuel carbureter, a by-pass compressed-air conduit, and automatic pressure-operated valves controlling the discharge from the compressor to said conduits and so arranged that the combustion-air discharge begins at a predetermined point in the compression stroke after the discharge of the by-pass air.

7. A compound heat engine comprising an internal-combustion high-pressure motor, a low-pressure motor operated by the high-pressure exhaust, an air-compressor coupled to the high-pressure motor for charging the same and having combustion-air and by-pass air discharge conduits, a governing valve controlling the combustion-air conduit, and a cross-conduit opening from the combustion-air conduit to the by-pass air conduit and containing an automatic pressure-operated relief valve.

In testimony whereof I have hereunto set my hand in the presence of two subscribing witnesses, the thirteenth day of June 1906.
